Primary Examiner — Karen E Eldridge Powers*(74) Attorney, Agent, or Firm* — Panitch Schwarze Belisario & Nadel LLP**CLAIM**

The ornamental design for a medical device having syringe port with locking mechanism, substantially as shown and described.

DESCRIPTION

FIG. 1 is a top perspective view of a medical device having syringe port with locking mechanism in accordance with our new design;

FIG. 2 is a bottom perspective view thereof;

FIG. 3 is a right elevation view thereof;

FIG. 4 is a top plan view thereof;

FIG. 5 is a front elevation view thereof;

FIG. 6 is a rear elevation view thereof;

FIG. 7 is a left elevation view thereof; and,

FIG. 8 is a bottom plan view thereof.

The broken lines in FIG. 5 illustrate features of the medical device that form no part of the claim.
